(57) **CLAIM**

The ornamental design for a connector piece for assembling toys and furniture, as shown and described.

DESCRIPTION

FIG. 1 is a front perspective view of a connector piece for assembling toys and furniture according to the present invention.

FIG. 2 is a front view of the connector piece for assembling toys and furniture of FIG. 1.

FIG. 3 is a rear view of the connector piece for assembling toys and furniture of FIG. 1.

FIG. 4 is a left side view of the connector piece for assembling toys and furniture of FIG. 1.

FIG. 5 is a right side view of the connector piece for assembling toys and furniture of FIG. 1.

FIG. 6 is a top view of the connector piece for assembling toys and furniture of FIG. 1; and,

FIG. 7 is a bottom view of the connector piece for assembling toys and furniture of FIG. 1.

The broken lines immediately adjacent the shaded areas represent the bounds of the claim and all other broken lines represent unclaimed portions of the article. None of the broken lines form a part of the claimed design.

1 Claim, 7 Drawing Sheets
